ABSTRACT

A manifold for pressurized air is located at the bottom of a container for granular materials and is in communication with the interior of the container through openings in the manifold. Each of the openings has an associated air-operated poppet valve for opening and closing the openings to control the passage of the pressurized air from the manifold into the container for mixing the granular material held in the container.

4 Claims, 3 Drawing Figures

FIG. 1

FIG. 2

FIG. 3

AIR BLENDER FOR GRANULAR MATERIALS

BACKGROUND OF THE INVENTION

1. Field of the Invention.

This invention is directed for use in the field of mixing or blending together a plurality of granular materials by using blasts of gases, preferably air, while the material is held in a container. More particularly, the invention is directed toward the manner of controlling the application of the blasts of air into the container by using valves to open and close the openings by which the gas is injected into the container.

2. Description of the Prior Art

The prior art is probably best illustrated and represented by U.S. Pat. Nos. 3,097,828 and 3,179,379. The 15 ultimate function and purpose of the instant invention, i.e. for the mixing together or blending of granular materials, is described quite well in the '379 patent. As described in somewhat greater detail therein, relatively short bursts of pressurized air are injected into the bottom of a container or a hopper which contains two or more granular materials which are to be mixed together in the container. The air blasts are introduced via an air manifold located at the bottom of the container having openings in communication with the interior of the 20 container through the tapered lower wall. The air is turned on and off by selectively opening and closing the conduit which carries the pressurized air from its source to the manifold. The '379 patent also describes the air currents which are produced by the injection of the blasts of air which are the results of the location and the orientation of the openings between the manifold and the container. There is no certainty that the mixing achieved with the instant invention results from the same pattern of air currents as described in the '379 patent.

One shortcoming of the prior art is that because the openings through which the pressurized air is injected into the hopper are located in the sloping walls of the container, there is likely to be some small amount of dead space immediately surrounding the bottom discharge opening where the granular material does not get thoroughly mixed.

Another shortcoming is that some type of filter element must be used somewhere between the opening into the container and the source of pressurized air to prevent granular material from entering into the air conduit, any control valves or the air source. Because these filters impede the flow of air and possibly for other reasons, the mixing air has to be at a relatively high pressure to produce acceptable blending of the ingredients.

SUMMARY

Similar to the prior art described above, the instant invention provides an air manifold at the bottom of the container or hopper. However, the openings from the manifold into the container are located immediately around the bottom discharge opening thereby virtually eliminating any dead air space from the mixing operation. Each of the openings has associated with it an air-operated poppet valve for opening and closing the openings. Air in the manifold is always maintained under some substantial amount of pressure and the air pressure applied to the poppet valves is raised and lowered for respectively closing and opening the openings between the air manifold and the container. Since some

substantial amount of air pressure is always maintained in the air manifold, the granular material is prevented from entering into the air manifold or elsewhere in the air supply which eliminates the need for filter elements in the supply air line. For this, and possibly other reasons, it has been found that the air can be injected into the container from the air manifold at a considerably lower pressure than in the prior art air mixers while producing at least equally good mixing.

As a further feature, the degree of travel of the poppet valve pistons can be varied to provide some amount of adjustment of the air blasts injected into the container from the manifold.

BRIEF DESCRIPTION OF THE DRAWING

FIG. 1 illustrates somewhat diagrammatically an air mixing system using any embodiment of the invention showing component parts of the system;

FIG. 2 is a view looking down into the interior of a 20 hopper or container; and

FIG. 3 is a partial sectioned elevational view of the lower part of the container showing an embodiment of the invention in detail.

DESCRIPTION OF THE PREFERRED EMBODIMENTS

The lower part of the hopper or bin 10 has the commonly-used inwardly sloped side walls 11, a centrally located discharge opening 12 at the bottom, an annular horizontal bottom wall 13 between the bottom edge of the sloping wall 11 and the outer edge of opening 12, and an inverted cone member 14 for closing the opening 12. By means not shown and not considered part of the instant invention, the closure 14 is raised and lowered to respectively open and close the discharge outlet 12 to permit the granular contents of the container 10 to be discharged through the bottom. The upper portion of the container 10, not shown, is constructed in the usual fashion and the materials are transported or fed into hopper 10 at the upper part. Located at the bottom of the hopper 10 and encircling the bottom discharge opening is an annular manifold 15 which receives pressurized air from an air supply 16 through a suitable conduit 17. A number of openings 20 from the manifold 15 into the bottom of container 10 are circumferentially spaced around the discharge opening 12. As can be best observed in FIG. 3, the top of the housing of air manifold 15 constitutes the bottom horizontal wall 13 of the container 10 in the area between the discharge opening 12 and the bottom edge of the sloped side wall 11. Each of the openings 20 provides communication between the interior of the container 10 and the manifold chamber 21. An outside sloping portion of the housing of manifold 15, generally designated by reference numeral 22, also serves as a passage by which material contained in container 10 is funneled out of the container as it leaves through the discharge opening 12. In FIG. 3, the inverted cone closure member 14 is shown in a position closing the discharge opening by being seated at its bottom edge against the housing of the manifold 15. To discharge the contents of the container 10 the closure 14 is lifted, by means not shown, to permit the granular material contained in the container 10 to discharge out through the bottom. An air inlet passage 23 provides means by which pressurized air is delivered from an air supply 16 through the conduit 17 and into the interior chamber 21. While

ordinarily there may be control valves or the like in the conduit path from air supply 16 to the manifold 15, since they do not constitute part of the instant invention, none are shown.

Mounted within the manifold 15, opposite and associated with each of the openings 20, is a poppet valve assembly generally designated by reference numeral 25. The poppet valve assembly comprises a cylinder housing 26 within which is slidably mounted a piston member 227 having a stem 28 which extends out beyond the end of cylinder housing 26 and has a seal 29 at its end facing the opening 20. An air inlet 30 through the housing 26 permits pressurized air from air supply 31 to enter into the cylinder chamber via suitable conduits 32. The cylinder and the piston are suitably sealed to make the cylinder air tight. A threaded member 35 extends through the housing 26 at the end of the valve opposite the stem end and has a slot 36 at one end, by which it can be threaded into or out of the housing, and a stop 37 at its other end. The latter determines the degree of travel that the piston member 27 makes in the cylinder chamber. The threaded member 35 can be adjusted to increase or decrease the length of travel of the piston member 27.

In operation, initially the closure member 14 closes off the bottom discharge outlet 12 and granular material is deposited into the interior of the container 10. A solenoid controlled valve 38 is operated to permit air from air supply 31 to enter into the cylinder chamber of the poppet valve 25 so that the piston member 27 is driven to its furthest upward position to close off its associated opening 20 into the interior of the container 10. At the same time, air is being supplied from source 16 into the chamber 21 of the manifold 15 but at a pressure somewhat lower than that being applied to the piston of poppet valve assembly 25. This holds the valve piston so that it closes the opening 20 and none of the material can flow into the air manifold. For mixing or blending together materials contained in hopper 10, solenoid valve 38 is operated so that the air pressure applied into the cylinder of poppet valve 25 is reduced below that of the air pressure in chamber 21 so that the piston member 27 is driven away from the opening 20 and a blast of pressurized air is injected into the interior of the container 10 through the opening 20 from the manifold chamber 21. The duration of the air blast is a matter of choice and is dependent on a number of different factors such as the amounts and the types of materials being mixed, the degree of mixture that is desired, air pressures being used, etc. In any event, the blast of air does cause the ingredients contained in the container to swirl about so they become mixed together. It has been found that some degree of control of the mixing is also possible by adjusting the spacing between the sealing end of the poppet valve piston 27 and the opening 20 when the valve is opened. Apparently this affects the volume and velocity of the air passing from the manifold chamber 21 into the container and thereby has some effect on the mixing. Each of the poppet valve assemblies 25 can be individually and separately adjusted, if desired, but it is preferred that all of the valve pistons are operated together to open and close the openings 20 at the same time. However, in the event it should be found desirable or beneficial to operate each or any of the valves independently, this can be easily accomplished with the present invention. All that would be necessary is to provide a

separate air line from the air pressure source 31 with a separately operated control valve to each of the valve assemblies 25.

The following describes the use of the invention to thoroughly mix a 10 cubic foot batch of black and white granular material. The black material ranged in granular size from about 0.0937 inch to about 0.0070 inch and the white material ranged in granular size from about 0.0070 inch to about 0.0029 inch. The air in the manifold was at a pressure in the order of about 20 psi and the air pressure to close the poppet valve was in the order of about 100 psi. The openings 20 into the hopper were about $\frac{1}{2}$ inch diameter. The mixing took about 30 seconds with air injected into the hopper through the openings in blasts of $1\frac{1}{2}$ second duration with a $2\frac{1}{2}$ second pause between each blast.

These figures are illustrative and not limitative. It is known by those skilled in the art that different quantities of differently sized particles may require different pressures, burst times, etc.

As can be observed from the foregoing description, there is always air pressure which may range, for example, from about 10 to 125 psi at the openings 20 so that virtually none of the granular material in the container 10 will be able to enter into the manifold chamber or be able to get into the air supply conduit or back into the air supply itself, thereby eliminating the need for any filter elements or the like.

It can be observed that as a feature of this invention the hoppers or containers such as those illustrated in the prior art patents mentioned above, can easily be modified to accept the instant invention so that it is not necessary to discard or substantially redesign the entire container.

I claim:

1. An air blender for mixing granular materials comprising, in combination: a container for granular materials having a bottom discharge outlet; a movable closure for closing and opening said outlet for respectively holding and discharging the granular material; an annular air manifold located below said closure, said manifold having a chamber and a plurality of openings from said chamber communicating with the interior of said container through openings spaced around the discharge outlet; an inlet for pressurized air into the manifold chamber; an air operated piston member for each of said openings, each of said piston members located in a housing within the manifold chamber with the closing end of each piston located opposite and below each of said openings; and an air inlet into the housing for controlling the movement of the piston toward and away from its associated opening to selectively open and close said openings to control the passage of air from the manifold chamber into the container, whereby pressurized air is always present at said openings.

2. The invention as set forth in claim 1 further including means for adjusting the distance of travel of said piston member away from said opening for controlling the air flow from the manifold chamber to the opening.

3. The invention as set forth in claim 1 further including: a source of pressurized air coupled to the air inlet of said manifold chamber; a source of pressurized air at a pressure greater than said first mentioned source; conduit means coupling said latter source to each of said piston housing air inlets; and control valve means for selectively blocking and allowing passage of pres-

surized air through said conduit means to said piston housings for controlling the operation of said piston members.

4. The invention as set forth in claim 2 wherein said means for adjusting the travel of said piston, comprises: a stop member located within said piston housing for

stopping said piston member as it moves away from said opening; and means for adjustably setting said stop member to stop said piston member closer to or further from the opening.

[57] **ABSTRACT**

A manifold for pressurized air is located at the bottom of a container for granular materials and is in communication with the interior of the container through openings in the manifold. Each of the openings has an associated air-operated poppet valve for opening and closing the openings to control the passage of the pressurized air from the manifold into the container for mixing the granular material held in the container.

REEXAMINATION CERTIFICATE
ISSUED UNDER 35 U.S.C. 307

THE PATENT IS HEREBY AMENDED AS
INDICATED BELOW.

Matter enclosed in heavy brackets [] appeared in the patent, but has been deleted and is no longer a part of the patent; matter printed in italics indicates additions made to the patent.

AS A RESULT OF REEXAMINATION, IT HAS
BEEN DETERMINED THAT:

Claim 1 is determined to be patentable as amended.

Claims 2-4 dependent on an amended claim, are determined to be patentable.

New claims 5-7 are added and determined to be patentable.

1. An air blender for mixing granular materials comprising, in combination: a container for granular materials having a bottom discharge outlet; 25
a movable closure for closing and opening said outlet for respectively holding and discharging the granular material; 30
an annular air manifold located below said closure, said manifold having a chamber and a plurality of openings from said chamber communicating with the interior of said container through openings spaced around the discharge outlet; 35
an inlet for continuously feeding pressurized air into the manifold chamber; 40
an air operated piston member for each of said openings, each of said piston members located in a housing within the manifold chamber with the closing end of each piston located opposite and below each of said openings;

45

50

55

60

65

end of each piston located opposite and below each of said openings; and
an air inlet into the *piston* housing for controlling the movement of the piston toward and away from its associated opening to selectively open and close said openings to control the passage of air from the manifold chamber into the container, whereby pressurized air is always present at said openings.
5. *The invention as set forth in claim 1 wherein the pressurized air fed into the manifold chamber is at a substantially constant pressure.*
6. *The invention as in claim 1 wherein the piston housing air inlet is located outside the manifold.*
7. *An air blender for mixing granular materials comprising, in combination: a container for granular materials having a bottom discharge outlet;*
a movable closure for closing and opening said outlet for respectively holding and discharging the granular material;
an annular air manifold located below said closure, said manifold having a chamber and a plurality of openings from said chamber communicating with the interior of said container through openings spaced around the discharge outlet;
an air inlet into the manifold chamber;
means for continuously feeding pressurized air at a substantially constant pressure to said manifold air inlet;
an air operated piston member for each of said openings, each of said piston members located in a housing within the manifold chamber with the closing end of each piston located opposite and below each of said openings;
an air inlet into the piston housing; and
means for feeding air at selectively changing pressure levels into said piston housing inlet for controlling the movement of the piston toward and away from its associated opening to selectively open and close said openings to control the passage of air from the manifold chamber into the container.
